UNITED STATES PATENT OFFICE.

UTLEY WEDGE, OF ARDMORE, PENNSYLVANIA, ASSIGNOR TO THE FURNACE PATENT COMPANY, OF PHILADELPHIA, PENNSYLVANIA, A CORPORATION OF PENNSYLVANIA.

FURNACE.

1,195,424.

Specification of Letters Patent. Patented Aug. 22, 1916.

Application filed January 20, 1910, Serial No. 539,134. Renewed January 20, 1916. Serial No. 73,210.

To all whom it may concern:

Be it known that I, UTLEY WEDGE, a citizen of the United States, residing in Ardmore, Pennsylvania, have invented certain 5 Improvements in Furnaces, of which the following is a specification.

The object of my invention is to so construct a furnace designed for heating or roasting ores, concentrates, or the like, as to 10 provide for the addition to the material under treatment, at an intermediate stage of such treatment, of fluxes, reagents, or the like, hereinafter, for convenience, referred to as a reagent, for combination with or action upon the material during the final stage 15 of its treatment. This object I attain in the manner hereinafter set forth, reference being had to the accompanying drawing, in which—

20 Figure 1 represents, in vertical section, a furnace constructed in accordance with my invention; Fig. 2 is a similar section of the lower portion of the furnace, illustrating a modification, and Fig. 3 is a similar section 25 illustrating a type of furnace, which, in the lower section, is muffle-fired, this view also illustrating a special feature of my invention not shown in the other views.

In the drawing, 1 represents the outer wall 30 of the furnace, 2 a series of superposed hearths and 3 a central hollow shaft, carrying radial arms 5 which project into the working chambers of the furnace and are intended to carry stirring and feeding blades 35 or rabbles of any appropriate character (not shown) these feeding blades or rabbles serving to mix the material lying upon the hearths of the furnace and to convey the same over said hearths from the inner to the 40 outer or from the outer to the inner portions of the hearth.

Preferably the roof of the furnace serves as a heating or drying floor for the green ore or concentrate and the shaft 3 is provided 45 with any suitable feeding device whereby the ore is deposited upon the uppermost hearth of the furnace through a trapped or luted passage or passages in order to prevent the escape of gas from the uppermost 50 working chamber into the room or apartment in which the furnace is situated.

The furnace may, for convenience, be said to be divided into two heating zones, the upper heating zone comprising, in the present instance, the four upper hearths and

having an air inlet 7 and a gas outlet 9, and the lower heating zone comprising the three lower hearths and having air inlet or inlets 10 and gas outlet 11, or, if desired, gas escaping from the lower heating zone may 60 pass upwardly through the upper heating zone to the gas outlet of said upper heating zone.

The passages for the material from the lower hearth of the upper heating zone to 65 the upper hearth of the lower heating zone may, if desired, be sealed against the flow of gas, the means shown in the present instance for effecting such seal being a shelf 12 upon which the material flowing through 70 the passage 6 is supported so as to back up the material into said passage and thereby seal the same, the material being removed from the shelf 12 at intervals by means of scrapers 13 attached to the stirrer arms 5 in 75 the upper working chamber of the lower heating zone of the furnace, and a fresh supply of material then flowing onto the shelf from the passage 6, and being removed in its turn, and so on, indefinitely. 80

In order to effect the admixture, with the material traversing the lower heating zone of the furnace, of the desired reagent, I provide, between the arch of the uppermost working chamber of said lower heating zone 85 of the furnace and the hearth of the lowermost working chamber of the upper heating zone of the furnace, means for feeding said reagent into said upper chamber of the lower heating zone. In the present instance, 90 this feeding device comprises one or more tubes 14, each having, at its outer end, a feed hopper 15 and communicating at its inner end with said upper working chamber of the lower heating zone of the furnace, 95 the tube containing a screw conveyer 16 or being provided with other means whereby the desired reagent may be fed through the same, or, because of the large diameter of the central shaft 3 the reagent may be supplied to the lower heating zone of the furnace from the interior of said shaft. Fig. 2 illustrates one means for accomplishing this result. The hopper 15 and feed tube 14 are mounted upon and rotate with the shaft 3, 100 the hopper being contained within said shaft, and the feed tube having therein a screw conveyer 16 whose shaft projects inwardly beyond the lower portion of the hopper and is provided with a bevel wheel 105 110

17 which meshes with a bevel wheel 19 on the upper end of a shaft 20, the latter turning in suitable bearings in the shaft 3, and having, at its lower end, a bevel wheel 21
5 which meshes with a bevel wheel 22 at the inner end of a short horizontal shaft 23, adapted to a bearing in the hub of the large bevel wheel at the bottom of the shaft 3, the outer end of said shaft 23 having a spur
10 wheel 24 which meshes with a fixed annular rack 25 on the bottom of the furnace structure.

My improved furnace is adapted for the introduction of a flux for sintering or agglomerating, in the lower heating zone of the furnace, material which has been desulfurized or calcined during its passage through the upper member, or for the combination with the material traversing the 20 lower heating zone of the furnace of a reagent for acting upon and splitting up compounds formed by the previous roasting of the material in the upper member of the furnace, such for instance, as salt for chloridizing purposes or carbonaceous matter 25 for combining with sulfur contained in the material delivered from said upper member of the furnace, or other and analogous uses which will suggest themselves to those skilled in the art to which my invention appertains.

The two heating zones of the furnace may, in some cases, be in open communication with one another, instead of having 35 said communication sealed against the flow of gas from one heating zone to the other.

In the furnace shown in Fig. 3 the treating chambers of the lower heating zone of the furnace are muffle-fired, the heating 40 gases being derived from a furnace or fireplace 26 and conveyed through suitable flues into the heating chambers 27 interposed between the arches and hearths of the treating chambers in said lower heating zone of the furnace, the heating gases escaping from 45 these chambers 27 through suitable outlet flues 27^a at the opposite side of the furnace.

Air for oxidizing purposes may be introduced into one or more of the treating 50 chambers in the lower heating zone of the furnace directly through openings in the side walls of the furnace, as shown for instance at 29, but I prefer to employ for this purpose preheated air and to effect such preheating of the air in the upper heating zone of the furnace, as for instance by passing it through a chamber 30 interposed between the arch of one treating chamber and the 55 hearth of a superposed treating chamber in said upper heating zone of the furnace, for by this means I not only effect the desired preheating of the air but I also abstract heat from the arch and hearth and thereby maintain a relatively low temperature in 60 the upper heating zone of the furnace, which

will prevent the overheating of the ore in its passage through the same.

The air heating chamber 30 communicates with a flue 31 (or any desired number of such flues) contained in the side walls of 70 the furnace, said flue (or each of the flues) communicating through suitable stoppered or dampered openings 32 with any desired treating chambers in the lower heating zone 75 of the furnace, and preferably also communicating through similar stoppered or dampered openings 33 with one or more of the heating chambers 27 in order to facilitate or improve the combustion of the heating gases therein. 80

I claim:

1. A roasting or like furnace having primary and secondary heating members, means for preventing flow of gas from one heating member to the other, means for effecting the discharge of gas from each member independently of the other and a mechanical conveyer for delivering a regulated supply of reagent to the material under treatment in the secondary heating member 90 of the furnace.

2. A roasting or like furnace having a plurality of superposed hearths, one of the hearths in the upper portion of the furnace being chambered, means for admitting air 95 to said chamber, and means for conveying the air heated in its passage through said chamber to a treating chamber in the lower portion of the furnace.

3. A roasting or like furnace having a 100 plurality of superposed hearths and presenting primary and secondary members communicating with one another through a passage sealed against the flow of gas, means for stirring or agitating and feeding forward the material contained in each member of the furnace, and means for feeding a reagent to the material in the secondary member of the furnace. 105

4. A roasting or like furnace having primary and secondary heating members communicating with each other through a passage sealed against the flow of gas, means for stirring or agitating and feeding forward 110 the material contained in each heating member of the furnace, a mechanical conveyer for delivering a regulated supply of a reagent to the material traversing the secondary heating member of the furnace, and means for supplying air to and removing gas 115 from each heating member of the furnace independently. 120

5. A roasting or like furnace having primary and secondary members, means for directly heating the primary member, means for muffle heating said secondary member, and means for supplying a reagent to the material which is being treated in the secondary member of the furnace. 125

6. A roasting or like furnace having pri- 130

- mary and secondary members, means for directly heating the primary member, means for muffle heating the secondary member of the furnace, means for supplying a reagent 5 to the material which is being treated in the secondary member of the furnace, and means for introducing air to said secondary member of the furnace.
7. A roasting or like furnace having primary and secondary members, means for directly heating the primary member, means for muffle heating the secondary member of the furnace, means for supplying a reagent to the material which is being treated in the 10 secondary member of the furnace, and means for introducing air into and discharging the gases from said secondary member of the furnace.
8. A roasting or like furnace having primary and secondary members, means for supplying a reagent to the material which is being treated in the secondary member of the furnace, and means for heating air in the primary member of the furnace and conveying 15 it to the secondary member of the furnace.
9. A roasting or like furnace having primary and secondary members, means for muffle heating the secondary member of the furnace, means for supplying a reagent to the material which is being treated in the secondary member of the furnace, and means for heating air in the primary member of the furnace and conveying it to the secondary 20 member of the furnace.
10. A roasting or like furnace having a plurality of superposed hearths and presenting primary and secondary members in communication with one another, means for feeding a reagent to the material traversing the secondary member of the furnace, and means for heating air in the primary member of the furnace and conveying it to the secondary member of the furnace.
11. A roasting or like furnace having a plurality of superposed hearths and presenting primary and secondary members in communication with one another, means for muffle heating the secondary member of the furnace, means for feeding a reagent to the material traversing the secondary member of the furnace, and means for heating air in the primary member of the furnace and
- conveying said heated air to the secondary member of the furnace.
12. A roasting or like furnace having a series of superposed treating chambers, each with hearth and arch, an air heating chamber interposed between the arch of one treating chamber and the hearth of the chamber above it, and means whereby air heated in said chamber is conveyed to a treating chamber of the furnace for use therein.
13. A roasting or like furnace comprising primary and secondary members, means for muffle heating the secondary member of the furnace, and means for heating air in the primary member of the furnace and conveying 60 said heated air to the secondary member of the furnace.
14. A roasting or like furnace having primary and secondary members, means for muffle heating the secondary member of the furnace, means for heating air in the primary member of the furnace, and means for conveying 65 said heated air to the treating chamber or chambers of the secondary member of the furnace and to the heating gas chambers of the muffle.
15. A roasting or like furnace having a plurality of superposed treating chambers and presenting primary and secondary members in communication with one another, means for muffle heating the lower member of the furnace, and means for heating air in 70 the upper member of the furnace and conveying it to the lower member of the same.
16. A roasting or like furnace having a plurality of superposed treating chambers and presenting primary and secondary members in communication with one another, means for muffle heating the lower member of the furnace, and means for heating air in the upper member of the furnace and conveying said heated air to the treating chamber or chambers of the lower member and to the heating gas chamber or chambers of the muffle.
- In testimony whereof, I have signed my name to this specification, in the presence of 100 two subscribing witnesses.

UTLEY WEDGE.
